MULTILENS MAGNIFIER

Albert H. Blum, Irondequoit, N. Y., assignor to
Bausch & Lomb Optical Company, Rochester,
N. Y., a corporation of New York

Application November 21, 1951, Serial No. 17,491

Term of patent 14 years

(Cl. D57—1)

To all whom it may concern:

Be it known that I, Albert H. Blum, a citizen of the United States and a resident of the town of Irondequoit, county of Monroe, and State of New York, have invented a new, original, and ornamental Design for a Multilens Magnifier, of which the following is a specification, reference being had to the accompanying drawing, forming a part hereof.

Fig. 1 is a front elevational view of a multilens magnifier, showing my new design.

Fig. 2 is a side view thereof.

Fig. 3 is a sectional view taken on line 3—3 of Fig. 1.

Fig. 4 is a sectional view taken on line 4—4 of Fig. 1.

Fig. 5 is a sectional view taken on line 5—5 of Fig. 1.

Fig. 6 is a sectional view taken on line 6—6 of Fig. 1.

I claim:

The ornamental design for a multilens magnifier, substantially as shown.

ALBERT H. BLUM.
